UNITED STATES PATENT OFFICE.

LAVERN M. MERKLEY, OF BLACKFOOT, IDAHO.

TRACTION-ENGINE.

958,816.

Specification of Letters Patent. Patented May 24, 1910.

Application filed November 18, 1908. Serial No. 463,330.

To all whom it may concern:

Be it known that I, LAVERN M. MERKLEY, a citizen of the United States, residing at Blackfoot, in the county of Bingham and State of Idaho, have invented certain new and useful Improvements in Traction-Engines, of which the following is a specification, reference being had to the accompanying drawings.

10 This invention relates to improvements in traction engines or vehicles for road and farm purposes.

The object of the invention is to improve the construction and operation of machines 15 of this character and thereby render them more durable and efficient.

With the above and other objects in view, the invention consists of the novel features of construction and the combination and arrangement of parts hereinafter fully described and claimed, and illustrated in the accompanying drawings, in which—

Figure 1 is a top plan view with parts broken away and in section of the improved 25 traction engine; Fig. 2 is a vertical longitudinal section taken on the plane indicated by the line 2—2 in Fig. 1; Fig. 3 is a vertical transverse section taken on the plane indicated by the line 3—3 in Fig. 1; Fig. 4 is a 30 detail longitudinal section showing one of the clutch operating shafts and its connections; Fig. 5 is a detail perspective of one of the corner posts; Fig. 6 is a similar view of one corner of the lower frame showing 35 the bearing plate for the corner post; and Fig. 7 is a detail cross section through the rim of one of the traction wheels.

In the drawings 1 denotes the lower frame or running gear and 2 the upper or body 40 frame which is resiliently supported above the former and which carries the gas engine or other motor 3 and its appurtenances and which may also be used for supporting a load of any description. The lower frame 45 1 is constructed of metal bars and is of open rectangular shape and suitably reinforced by longitudinal bars 4 and transverse brace bars 5. Projecting forwardly from the center of its front end is a reach bar 6 the forward 50 end of which is cylindrical and mounted for rotation in a bearing 7 arranged upon the top of a fifth wheel plate 7^a. The latter is rotatably mounted upon a similar fifth wheel plate 8^a which is secured to the front axle 8. 55 Depending from the center of the plate 7^a

is a pivot stud 7^b which passes through the vertical opening formed in the plate 8^a and axle 8, a nut 7^c being arranged upon the threaded lower end of the pivot 7^b to retain said parts in engagement with each other. 60 It will be noted that this construction prevents the frame from twisting when traveling over uneven ground. The axle 8 has its central portion dropped and it carries two steering wheels 9 which are comparatively 65 large and disposed well in advance of the front end of the lower frame 1 so that a very short turn can be made by the machine. The rear axle 10 is made in two sections connected by a differential gear 11 of the usual 70 form and having at their outer ends improved traction wheels 12. The sections of the axle 10 are suitably journaled in bearings upon the lower frame 1 and the provision of the differential gear between them 75 permits one wheel to turn faster than the other in turning the machine.

The traction wheels 12 each consist of a hub, spokes radiating therefrom and an improved rim 13 consisting of a centrally disposed continuous annular tread 14 projecting from an annular base portion 15 and having on its opposite sides and arranged in staggered relation blades 16 which unite the portions 14, 15 and form pockets between them. 80 The outer edges of the blades 16 are disposed in the plane of the periphery of the tread portion 14, which latter is broad enough to support the weight of the machine and its load upon firm ground, but when the machine travels over soft ground or mud and the tread portion 14 sinks into the same the blade 16 will also enter the ground and prevent the wheel from slipping. 90

The steering of the machine is effected by turning a hand wheel 17 fixed to the upper end of a vertical shaft rotatably mounted in bearings 18 and carrying a sprocket wheel 19 around which is passed a chain 20. The latter has its ends fixed to the outer portions of the front axle 8 and its intermediate portions are passed around guide rollers 21 journaled between upper and lower transversely extending plates secured to the bar or beam 6. This guide device for the steering chain prevents the latter from interfering with the front wheels when a short turn is made by the machine. The upper frame 2 is also constructed of metal bars and is of open rectangular shape reinforced by longitudinal 100 105 110

bars 23 and covered by metal plates or sheets 24 which form a platform upon which the engine 3 and other parts of a load are supported. The resilient connection between the upper and lower frame is effected by providing four corner posts 25, the upper ends of which are provided with right angular blocks 26 which are arranged in the four corners of the upper frame 2 and bolted or riveted to its side and end bars so that the 10 posts 25 depend and project through and slide in openings 27 formed in triangular-shaped corner plates 28 secured upon the four corners of the lower frame 1, as more 15 clearly shown in Fig. 6. Coil springs 29 surround the posts 25 and support the upper frame 2 and the load thereon.

The engine 3 is connected to the differential gear 11 by a gearing which will permit the machine to be driven forwardly at different speeds and to be driven rearwardly without changing the speed or reversing the engine. This gearing is clearly shown in Figs. 1 and 2 of the drawings and comprises a main drive shaft 30, a direct drive countershaft 31 and a reverse drive countershaft 32. These three shafts are suitably journaled in hangers 33 depending from the upper frame 2. Fixed to the shaft 30 is a sprocket wheel 34 connected by a sprocket chain 35 to the shaft of the engine 3 and having in its opposite faces openings or seats to receive clutch pins 36 upon sprocket wheels 37, 38 slidably and rotatably arranged upon the shaft 30 upon opposite sides of the sprocket 34. The sprocket 37 is comparatively large and is connected by a chain 39 to the sprocket wheel 40 on the shaft 31 and the sprocket 38 is integral with a smaller sprocket 41, which latter is connected by a chain 42 to a comparatively large sprocket 43 on the shaft 31. Owing to the size and arrangement of the sprockets 37, 40, 41, 43 it will be seen that when the sprocket 38 is locked to the sprocket 34 the shaft 31 will be driven at a lower speed than it would be driven when the sprocket 37 is locked to said sprocket 34. If a still higher speed is desired the chain 42 may be lengthened and transferred from the sprocket 41 to the sprocket 38 and if a still higher speed is desired the chain 39 may be shortened and transferred from the sprocket 40 to a smaller sprocket 44 fixed to the shaft 31. The shaft 31 is connected to the differential gear 11 by a sprocket chain 45 which passes over a sprocket wheel 46 on said shaft 31. The reversing gear comprises a gear 47 fixed to the shaft 30 and in mesh with a gear 48 which is fixedly mounted upon the shaft 32 and carries a clutch member to be engaged by a similar clutch member 49 carried by a sprocket wheel 50 which is slidably and rotatably arranged on the shaft 32 and connected by a chain 51 to a sprocket wheel 52 on the shaft 31.

The three shiftable sprocket wheels 37, 38, and 50 are controlled by three hand levers 53, 54, and 55 arranged adjacent to the front end of the upper frame. Each of said levers projects through a slot in the 70 platform and is fixed to one end of a longitudinal shaft 56 having cylindrical portions journaled in bearings 57 upon the bottom of the platform, as clearly shown in Fig. 4 of the drawings. Each of said levers 75 is also provided with a spring projected and hand retracted locking pawl 58 which contacts with a locking rack 59. Depending from each of the shafts 56 is a forked arm 60, the ends of which carry pivot studs 61 80 to enter a ring 62 arranged for rotation in an annular groove in the hub of one of said sprocket wheels 37, 38, 50. It will be seen that when any of the levers 53, 54, 55 are oscillated the shafts 56 will be rocked and 85 the arms 60 of the latter will shift said sprocket wheels.

From the foregoing it will be seen that the invention provides an exceedingly simple traction engine or vehicle which may 90 be produced at a comparatively small cost and will be strong and durable and very efficient for transporting agricultural implements or machines over roads, through fields and the like and which may also be 95 anchored or made stationary and used for driving threshing machines, saw mills and the like.

Having thus described the invention what is claimed is:

In a machine of the character described, the combination of upper and lower frames, spring devices for supporting the upper frame above the lower one, steering and driving wheels carried by the lower frame, a 105 differential gear on the axle of the driving wheels, said upper frame consisting of front and rear end bars uniting longitudinal side bars and longitudinal intermediate bars, angular bearing brackets depending from the 110 intermediate longitudinal bars, a main drive shaft journaled in said brackets, a reverse drive counter shaft journaled in said brackets, a direct drive counter shaft journaled in said brackets, meshing gears on the main 115 drive shaft and the reverse drive counter shaft, sprocket chain gearing between the direct and reverse drive counter shafts, and including the shiftable sprocket wheel, sprocket chain gearing between the direct 120 drive counter shaft and said differential gearing, the sprocket wheel 34 fixed to the main drive shaft, two sets of sprocket chain gearing between the main drive shaft and the direct drive counter shaft, and including 125 shiftable sprocket wheels arranged on opposite sides of the sprocket wheel fixed to said main drive shaft, the last mentioned shiftable sprocket wheels being adapted to be locked to said intermediate one for rota- 130

tion therewith, a top plate arranged on the upper frame and formed adjacent its front edge with transverse slots, longitudinal rock shafts journaled in bearings on the bottom of said plate, hand levers fixed to the forward ends of said rock shafts and working in the slots of said plate, locking devices for said hand levers, and arms depending from the rear portions of said rock

shafts for actuating the said shiftable 10 sprocket wheels.

In testimony whereof I hereunto affix my signature in the presence of two witnesses.

LAVERN M. MERKLEY.
